2 Claims. (Cl. 138—30)

The present invention relates to accumulators of liquid under pressure of the type including a rigid container provided with at least one inlet and outlet conduit for the liquid, and a flexible deformable bag fixed at one end to said container and filled with gas under pressure.

The object of the present invention is to provide an accumulator of this type which is better adapted to meet the requirements of practice than those existing prior to this invention, and, in particular, better protected against possible injury of the deformable bag.

Another object of the present invention is to devise an accumulator advantageous for use on aircraft.

With this object in view, according to an important feature of my invention, the orifice of the liquid conduit above mentioned which opens into the rigid container is provided with means for preventing the bag from engaging therewith while permitting the flow of liquid into and from said conduit as long as the bag is not applied against said orifice.

Other features of the present invention will result from the following description of an embodiment thereof given by way of example and illustrated in the accompanying drawing.

The only figure is a diagrammatic sectional view of an accumulator according to the invention.

The drawing shows a rigid container 1 forming the outer casing of the accumulator and a flexible and advantageously elastic bag 5 provided inside this container. Bag 5 may be simply attached to the accumulator 1 at 6. It forms a continuous partition between chambers 2 and 3, thus preventing the formation of an emulsion of gas in the oil. This bag is expanded or compressed according to the variations of volume of chamber 2 under the effect of variations of the oil pressure in chamber 3. In normal conditions, the pressures are practically equal inside and outside of bag 5.

In order to prevent an excessive expansion of bag 5 with a consequent risk of bursting, in the case of a sudden drop of the oil pressure in chamber 3, means may be provided in the wall of this bag, in the form of a small orifice, of a slot, of a valve or the like, adapted to afford the escape of air from bag 5, but preventing all circulation of oil from chamber 3 into the said bag. Such means are described in my co-pending application Ser. No. 229,641.

In the illustrated embodiment of the present invention, which offers particular advantages by

reason of its simple construction, bag 5 is secured at its upper end, at 6, to container 1, and is fitted at this point with a valve means for filling the same with gas under pressure. The lower end 25 of bag 5 is free in container 1 and its end portion is reinforced.

In the end of container 1 opposite to 6 is provided a port 27 for the inflow or outflow of liquid under pressure to be stored in the accumulator.

10 The communication across port 27 is controlled by a member 26 which closes this lower end of container 1. At its upper portion, member 26 comprises an axial bore in which is slidably mounted a plunger 28, urged upwardly by a spring

15 28 so as to cause its upper face to project above the upper face of member 26 into container 1. In the periphery of member 28, there is formed a groove 31 the height of which is such that, whatever be the position of plunger 28 in member

20 26, said groove 31 is always in communication with radial channels 30 provided in member 26. Groove 31 also communicates through radial channels 32, formed in plunger 28, with a central bore 31^a provided in said plunger, which bore

25 31^a communicates with port 27 and contains spring 29. The upper part 26^a of member 26 is engaged preferably with a certain play 33 in the lower portion 1^a of container 1. This play may, however, be dispensed with and in this case channels 30, 31, 32 become superfluous. The upper

30 part of plunger 28 is provided with radial channels 34 which communicate with the inside of container 1 when plunger 28 is raised, but which are closed when the latter is forced into member 26. Plunger 28 is movable in member 26 with a certain lateral play, such as $\frac{1}{16}$ mm. or the like.

The operation is as follows: When bag 5 is expanded and comes to bear against the upper 40 surface of member 26 and plunger 28, it drives plunger 28 into member 26, against the action of spring 29. The reinforced portion 25 of bag 5 is applied against a wall, which is continuous except for the slight play between member 26 and plunger 28 and between part 26^a and the inner wall of container 1. The said play, if any, should be so small as to avoid all damage to bag 5, even if the same be applied with considerable force.

50 Plunger 28 will also be forced into member 26, although bag 5 may be distant from the former, when the pressure in container 1 exceeds the pressure in conduit 27 and bore 31^a plus the strength of spring 29. In this event, the play 33 provided between member 26 and the wall of con-

tainer 1, as well as the play between member 26 and plunger 28 permit the outflow of a small supply of liquid which is sufficient to operate controls which require only a small power, such as the wing flaps of an aeroplane or the like.

The normal position shown by Fig. 1, in which plunger 28 projects from member 26 and uncovers the channels 34, affords a much greater in-and outflow.

The foregoing description is not intended to limit my invention which extends to any changes or modifications comprehended within the scope of the appended claims.

I claim:

1. An accumulator of liquid under pressure which comprises, in combination, a rigid container, at least one port for supply and discharge of liquid opening into one end of said rigid container, a flexible deformable bag in said container fixed at one point thereof to the other end of the same and filled with gas under pressure, said bag being incapable to resist said pressure unless supported, and valve means, in said port, for controlling the flow of said liquid therethrough, said valve means being adapted to be flush with the inner wall of said container at least when said bag is bearing thereon.

2. An accumulator of liquid under pressure which comprises, in combination, a rigid container, at least one port for supply and discharge of liquid opening into one end of said rigid container, a flexible deformable bag in said container fixed at one point thereof to the other end of the same and filled with gas under pressure, said bag being incapable to resist said pressure unless supported, and valve means inserted into said port, said valve means including a member fixed to the container and forming the valve seat, a movable valve element adapted to cooperate with said seat so as either to project into said container or to be driven into said fixed member, in flush relation to the inner face thereof, and elastic means for urging said movable valve element toward the first mentioned position thereof, in which it affords communication across said port between the inside of said rigid container and the outside, said valve means being mounted with a certain play in said port so as to permit a small flow of said liquid even when the movable valve element is in the closed position.

JEAN MERCIER.
